UNITED STATES PATENT OFFICE.

FRANCIS M. NEFF, OF HURON, DAKOTA TERRITORY.

COMPOSITOR'S FRAME.

SPECIFICATION forming part of Letters Patent No. 362,394, dated May 3, 1887.

Application filed January 28, 1887. Serial No. 225,803. (No model.)

To all whom it may concern:

Be it known that I, FRANCIS M. NEFF, a citizen of the United States, residing at Huron, in the county of Beadle and Territory of Dakota, have invented a new and useful Improvement in Compositors' Frames, of which the following is a specification.

This invention is a device adapted to be used in connection with a printer's lower case, for the purpose of saving compositors both labor and time in setting up matter.

It has been observed in practice that every article written on any subject will contain very similar numbers of certain short and much-needed words, such as "more," "all," "no," "though," and others. Advantage has been taken of this fact to design the herein-described invention, which consists of a rectangular frame containing boxes for the capitals, both large and small, and compartments each adapted to hold a number of one of such words, the said boxes and compartments being arranged substantially as hereinafter described, and illustrated in the accompanying drawings, in which—

25 Figure 1 represents a plan view of the device. Fig. 2 represents an edge view of the same, resting upon the cases of a printer's stand; and Fig. 3 represents a perspective view of the rear side of the device to show the attachment of the legs thereto.

Referring to the accompanying drawings, A designates the rectangular body or frame of the device, the dimensions of which frame are about twenty-four inches long by thirteen 35 inches broad.

a is a spring copy-holder of ordinary construction attached to the upper edge of the frame, and with its bend bearing against a block, a', secured upon said edge, as seen in 40 Fig. 1.

B B are legs pivoted at the points b b at the back of the frame, at equal distances from the ends thereof, and capable of having their ends turned laterally upon the frame or toward and 45 from the ends thereof.

C C are legs, having their upper ends pivoted to the legs B. The said ends of the legs C are rounded concentrically with their pivot-points c c, so that they are capable of being 50 turned rearward thereon.

The frame, when used in connection with

the cases, has the legs B B resting in two of the small boxes in the upper row of the lower case, and the legs C C inclined rearward and having their ends in certain of the boxes of the upper case. Thus any desired inclination can be given to the frame, and it can be used with any sized cases, as the legs B can be turned outward when the boxes are large and inward when they are small. 55

It is intended to use the lower case only with the device. 60

D D are the boxes for the large capitals, preferably situated at the right upper corner of the device; and E E are the boxes for the 65 small capitals, situated, preferably, at the left upper corner of the same. The members of both sets of boxes are of equal size, and arranged in the well-known manner, and both between and below the two sets of boxes are 70 the equidistant longitudinal grooves F F, which are about one-half inch distant from each other. The grooves are each divided into compartments or pockets f f by the transverse plates f' f', just wide enough to make suitable partitions in the grooves, and far enough apart to have the desired form of set-up type placed snugly in the pockets between them, each word being repeated a proper number of times, and, consequently, filling a number of pockets. 75

I do not desire to limit myself to any particular words, nor to any special number of words, nor the exact arrangement of the words shown in the drawings. That arrangement is, however, preferable, as the words fill more or less pockets, according to the frequency or unfrequency of their use. 85

The words used are ninety-one (91) in number, according to the longitudinal arrangement in the grooves, as follows: so, it, is, on, to, no, 90 of, be, by, or, he, in, do, up, we, an, as, at, has, had, him, our, one, not, but, who, can, for, ing, now, was, see, the, you, and, any, are, all, his, its, each, gone, good, give, will, were, with, when, what, here, have, soon, may, this, that, 95 then, they, tion, them, been, done, down, come, into, more, most, must, many, much, over, only, such, some, very, your, upon, from, every, could, other, these, those, until, under, their, where, which, would, should, though, 100 through.

It will be observed that some of the above

are not complete words, but merely terminations of classes of such words as are frequently used.

My experience has caused me to believe the 5 above arrangement is among the best; but other printers might differ from me in opinion, which is one reason that I do not wish to claim that exact arrangement.

The back of the frame is preferably made of 10 plank, with the grooves cut therein. Between each two sets of words a thicker partition is preferably inserted to mark the ends of each set.

Having described my invention, I claim—
15 1. A device for saving compositors time and labor when setting type, which device consists of a frame provided with longitudinal sets of grooves across its front surface and partitions across said grooves to convert the latter into 20 pockets or compartments, each a proper size to hold a number of type set up to form a word or part of a word, substantially as specified.

2. The combination, with the frame provided with the boxes for the capitals and the 25 pockets or compartments for the type set up to form words or parts of words, which pockets are formed by longitudinal grooves and the partitions therein, of the legs pivoted to the back of the frame in such a manner as to turn laterally thereon, and the legs pivoted upon 30 the former legs in such manner as to turn rearward and frontward with reference to the device, whereby the latter is rendered capable of being used with cases of different sizes, substantially as specified. 35

In testimony that I claim the foregoing as my own I have hereto affixed my signature in presence of two witnesses.

FRANCIS M. NEFF.
